US00D452332B1

(12) **United States Design Patent** (10) Patent No.: **US D452,332 S**
Blomquist et al. (45) Date of Patent: **** Dec. 18, 2001**

(54) **MODULAR RETAINING WALL BLOCK**

(75) Inventors: **Peter J. Blomquist**, Melbourne Beach, FL (US); **Todd P. Strand**, Marine on St. Croix, MN (US)

(73) Assignee: **Kiltie Corporation**, Oakdale, MN (US)

(**) Term: **14 Years**

(21) Appl. No.: **29/141,432**

(22) Filed: **May 4, 2001**

Related U.S. Application Data

(62) Division of application No. 29/112,434, filed on Oct. 15, 1999, now Pat. No. Des. 435,302, and a division of application No. 29/130,433, filed on Oct. 2, 2000, now Pat. No. Des. 447,573.

(57) **CLAIM**

The ornamental design for a modular retaining wall block, as shown and described.

DESCRIPTION

FIG. 1 is a perspective view of a modular retaining wall block of our new design;

FIG. 2 is a top plan view thereof;

FIG. 3 is a front elevational view thereof;

FIG. 4 is a side elevational view thereof, as taken from the left in FIGS. 1-3 (the right side is a mirror image of the left side);

FIG. 5 is a rear elevational view thereof; and,

FIG. 6 is a bottom plan view thereof.
